UNITED STATES PATENT OFFICE

2,566,276

EVAPORATIVE COOLING DEVICE

Arthur T. Wildey, Los Angeles, Calif.

Application May 2, 1947, Serial No. 745,557

1 Claim. (Cl. 261—104)

1

My present invention relates to an improved evaporative cooling device of the type especially designed for use with conventional cooling systems of motor vehicles and particularly designed to aid the cooling of the engine on long sustained climbs, or when traveling over hot desert areas.

Generally my invention comprises a pair of water containers supported adjacent the upper portion of the outer surface of the radiator, with water conveying strips withdrawing water by capillary action so that the air passing through the radiator passages will be cooled thus cooling the water in the radiator, and the moist air will improve the engine operation by providing moist air for carburetion.

In the accompanying drawings I have illustrated one complete example of the physical embodiment of my invention according to the best mode I have thus far devised, but it will be understood that various changes and alterations may be made in the exemplified structure within the scope of the appended claim.

In the drawings:

Figure 1 is a front elevational view of the cooler of my invention attached to a radiator;

Figure 2 is a side view thereof;

Figure 3 is a top plan view of the cooler;

Figures 4 and 5 are vertical sectional views at the indicated lines in Figure 3.

Referring now to the drawings, wherein I have illustrated the present preferred embodiment of my invention, I provide the radiator 10 which is of conventional construction, on which is mounted a pair of relatively spaced cans or containers 11 for water which is admitted through filler openings 12, closed by caps 13.

Hanger straps 14, having upper hooked ends 15, support the cans 11 in front of the radiator shell 16. The hanger straps 14 are held against accidental displacement from their spaced positions by fasteners 17 which, passing through the hangers, below the hooked end 15, engage the radiator 10. A horizontally disposed pipe or tube 18 is secured to the cans 11 in any suitable manner, as by welding or the like. The tube 18 extends between the cans 11 adjacent the upper ends thereof and communicates with the interior of the cans. The bottom of the tube 18 is provided with relatively spaced openings 19 and in this pipe, I provide a plurality of felt strips 20 which extend well down into the water in the cans, as shown in Figure 5, and outwardly and downwardly to be secured at their lower ends between straps 21 and 22 by rivets 23. The straps 21 and 22 are secured to the lower hooked ends 24, which support the cans 11, and are secured thereto by fasteners 25.

2

The cans, as shown, are relatively spaced apart, and the felt strips 20 depend vertically in the space between the cans so that air under pressure of the forward movement of the vehicle, coupled with the usual fan, will pass through the spaces between the vertical portions of the strips 20, and as the water in the cans is conveyed by the strips 20 into the path of air, the air will be cooled and capable of removing heat from the water in the radiator.

From the foregoing, it will now be seen that there is herein provided, a radiator cooler which accomplishes all the objects of this invention and others, including many advantages of great practical utility and commercial importance.

As many improvements may be made in this inventive concept and as many modifications may be made in the embodiment herein shown and described, it is to be understood that all matter herein is to be interpreted merely as illustrative, and not in a limiting sense.

Having thus fully described my invention what I claim as new and desire to secure by Letters Patent is:

25 An evaporating cooling means comprising a pair of spaced water tanks, a Z shaped bracket secured to each tank for supporting each tank in front of an apparatus to be cooled, a tube having slots therein connecting the tanks in spaced relation to each other, felt strips having the upper ends thereof positioned in the tube and a portion of the ends of the strips extending longitudinally of the tube in one direction to be immersed in the water of one of the tanks, and 30 the remaining portion of the ends of the strips extending longitudinally of the tube in the opposite direction to be immersed in the water in the other of said tanks, the opposite ends of the felt strips depending vertically from the tube in equal horizontal spaced relation to each other and a pair of strips secured to the lower ends of the felt strips and to the face of the tanks to retain the latter ends of the strips in their normal position.
